UNITED STATES PATENT OFFICE.

HENRY ROBERT SPENCER, OF JAMESTOWN, NEW YORK, ASSIGNOR TO KELLOGG SWITCHBOARD & SUPPLY COMPANY, OF CHICAGO, ILLINOIS, A CORPORATION OF ILLINOIS.

TELEPHONE APPARATUS.

Application filed April 17, 1924. Serial No. 707,024.

My invention relates to a telephone apparatus used in connection with a telephone system in which the well known super-imposed ringing principal is employed for 5 ringing or signalling a called for subscriber on a party telephone line without signalling the other subscribers on said party line.

An object of my invention is the provision of an alternating current relay which is simple and inexpensive in construction and very efficient in its operation.

Another object of my invention is the utilization of my alternating current relay in the subscriber's substation for effectively 15 connecting the call bell of said substation in circuit with the telephone line, to which said substation is connected, during the application of ringing current to said telephone line, and to disconnect said call bell during the 20 non-application of ringing current and during conversation so that no current will flow through said call bell thereby increasing the efficiency of the telephone system. Each 25 substation on the party line is provided with my alternating current relay which relay is associated with the call bell. When ringing current is applied to the said party line each one of said relays will operate to effectively connect the associated call bells with the 30 telephone line and when ringing current is not applied to the said line the said relays will operate to disconnect the call bells from said line so that no current will flow through the coils of said call bells thereby increasing 35 this efficiency of the telephone system and to effect better transmission.

The above features as well as others will be more particularly pointed out in the ensuing specification and for a clearer understanding of my invention reference may be had to the accompanying drawing in which like reference characters in the several views denote like parts, and in which;

Fig. 1 is a front elevation of the alternating current relay of my invention;

Fig. 2 is a top view of Fig. 1;

Fig. 3 is a left side elevation of Fig. 1;

Fig. 4 is a perspective view of the armature associated with the relay of my invention; and

Fig. 5 is a perspective view of the armature supporting frame.

Referring now more in detail to my invention as illustrated in the accompanying drawing it comprises a magnetizable core

1 around which is wound the usual windings 2 between the spool heads 3 which are secured to the core 1, said windings 2 having connection with the terminals 4 secured to one of the spool heads 3. A mounting bracket 5 is provided with an integrally formed ear 9 formed at right angles to the said bracket 5 and provided with an opening through which the threaded end of the core 1 extends and a nut 10 is provided which has screw-threaded engagement with said threaded end of said core to secure my relay to the mounting bracket 5.

An armature 15 is provided which has its end 16 reduced and provided with a pair of suitable transverse orifices 14. A supporting member 17 of suitable conducting material is provided which has a pair of integrally formed ears 18 properly spaced to permit the insertion of the reduced end 16 of the armature 15 and a trunnion pin 19 is provided in one of the ears 18 and adapted to engage one of the transverse orifices 14 in said end 16 while an adjustable screw 20 having its one end cone shaped extends through and has screw-threaded engagement with a suitably tapped orifice in the other ear 18, said cone shaped end extending into the other transverse orifice of the pair of transverse orifices 14 provided in the reduced end 16 of armature 15. The trunnion pin 19 and adjustable screw 20 serve to pivotally support the armature between the ears 18 of the supporting member 17. The screw 20 is adjustable to obtain the correct 90 pivotal movement of the armature 15, and a suitable lock nut 21 is provided for the screw 20 for maintaining said screw 20 in its adjusted position. A terminal 22 is integrally formed with the supporting member 95 17 for receiving an external conductor. A leaf spring 24 having a contact member 25 of suitable conducting material is provided and secured to the reduced end 16 of the armature 15 by suitable screws 26 which extend through suitable openings in the said leaf spring 24 and then have screw-threaded engagement with suitably tapped orifices in the armature 15. Another leaf spring 28 is provided which is secured near its one end 105 to the mounting bracket 5 by suitable screws 29, said leaf spring 28 being insulated from the bracket 5 and screws 29 by suitable insulation strips 30. The end 28' of spring 28 is adapted to receive an external conduc- 110

for the external conductor connected to said end 28' adapted to be connected in circuit with the external conductor connected to the terminal 22 when alternating current is flowing through winding of my relay via spring 28, contact 25 spring 24, armature 15, ears 18, member 17 and terminal 22.

The armature supporting member 17 is secured to the mounting bracket 5 by means of suitable screws 32 which pass through suitable openings in the said bracket 5 and through suitable openings in the insulation strip 33 which insulates the member 17 from the bracket 5, and then have screw-threaded engagement with suitably tapped orifices in the supporting member 17. The screws 32 are insulated from the mounting bracket 5 by suitable bushings. The armature supporting member 17 is secured to the bracket 5 in such a position that the free end of the leaf spring 24 is directly over and at right angles to the free end of the leaf spring 28, the contact member 25 being normally out of contactual engagement with the free end 25 of said leaf spring 28. The enlarged end 15' of the armature 15 is of such a shape and weight, and the armature 15 is pivotally suspended at such a point, that when the mounting plate is in its vertical mounting position as shown in Figs. 1 and 2, the contact member 25 of the leaf spring 24 is maintained out of engagement with the leaf spring 28, and the enlarged end 15' of armature 15 will be in alignment with only a small arcuate portion of the free end of the core 1. Now when alternating current is passing through the winding 2 of the coil of my relay, the core 1 is magnetized and will attract the armature 15 at its enlarged end 15' and due to the attraction of the magnetized core 1 and the said enlarged end 15' not being in direct alignment with the center of the free end of the core 1, the armature 15 will move about its pivots between the ears 18 of the member 17 until the enlarged end 15' is in direct alignment with the free end of the core 1, at which position the contact member 25 secured to the leaf spring 24 will be in contactual engagement with the free end of the leaf spring 28. My alternating current relay will remain energized so long as alternating current is passing through its winding 2 whereby the contact member 25 remains in contactual engagement with the leaf spring 28 to maintain a closed circuit between the terminals 28' and 22. When current no longer flows through the winding 2 of my relay, the core 1 demagnetizes whereupon the armature 15 re-stores to its normal resting position by gravity whereby the contact member 25 disengages the leaf spring 28 to open the circuit with which the relay may be associated.

The center of gravity of the armature 15, while said armature is in its pivotally

mounted position, is such that the armature 15 will normally rest in such position that the contact member 25 will not engage the leaf spring 28 when no current is flowing through the winding 2.

70

Having described a particular embodiment of my invention as illustrated, it is to be understood that I do not wish to be limited to the exact structure as described and illustrated as changes and modifications will readily suggest themselves to those skilled in the art, but that I intend to cover all that which may come within the scope and spirit of the appended claims.

75

What I claim as new and desire to secure by United States Letters Patent is:

1. A device of the class described including a magnetizable core, a winding for said core, said core and winding forming a single mountable unit, a mounting bracket having an integrally formed ear, means for securing said unit to said ear, a pendulous armature having its one end reduced and its other end enlarged, means secured to said mounting bracket for pivotally supporting said armature at its reduced end and for positioning said enlarged end in a vertical plane parallel to the axis of said core and in operative position relative to one end of said magnetizable core, said supporting means including an adjustable screw adapted to adjust the pivotal movement of the said armature and to be locked in its adjusted position, a contact spring secured to said armature, a contact spring secured to said bracket, and means for connecting operating current to the winding of said core to energize said core whereby said armature is pivotally moved in a plane parallel to the face of the core of said electromagnet, to effect contactual engagement of said contact springs.

90

2. A device of the class described including an electromagnet, a mounting bracket having an integrally formed ear member, means for securing said electromagnet on said integrally formed ear member, a pendulous armature having its one end reduced and its other end enlarged, means for pivotally supporting said armature upon said mounting bracket said enlarged end being positioned in a vertical plane parallel to the axis of said electro-magnet and in operative position relative to the core of said electromagnet, said supporting means including an adjustable screw adapted to adjust the pivotal movement of the armature and to be locked in its adjusted positions, a contact spring secured to the reduced end of said armature, a contact spring secured to said bracket and having one of its ends in operative position relative to said first contact spring, said electromagnet operable to attract said enlarged end of said armature to move the same in a plane parallel to the face of the core of said electromagnet to

cause said contact springs to make contactual engagement when operating current is flowing through said electromagnet, said enlarged end of said armature also adapted 5 to restore said contact springs to discontinue the contactual engagement of said contact springs.

3. An alternating current relay of the class described including an electromagnet, a 10 mounting member for supporting said electromagnet, a pendulous armature pivotally supported in a vertical plane parallel to the axis of said electromagnet and in operative position relative to the core of said electromagnet by means including an adjustable 15 screw adapted to adjust the pivotal movement of said armature and to be locked in its adjusted position, a pair of contact springs normally disengaging each other, one of said 20 contact springs secured to said armature and the other of said pair secured to said mounting member, means for energizing said electromagnet to operate said armature and move the same in a plane parallel to the face of 25 the core of said electromagnet to cause said contact springs to engage each other to close a circuit through said contact springs, said armature operable by gravity to discontinue the engagement of said contact springs to 30 open the circuit through said contact springs and pivotally balanced in its normal position to maintain said contact springs out of contactual engagement.

4. A device of the class described including an electromagnet, a mounting member, means for securing said electromagnet to said mounting member, a pendulous armature having a contact spring secured thereto to pivotally supported in a vertical plane 35 parallel to the axis of said electromagnet and in operative relation of the core of said electromagnet by means including an adjustable screw adapted to adjust the pivotal movement of said armature and to be locked 40 in its adjusted position, another contact spring secured to said mounting plate, said armature adapted to be operated by said electromagnet to move the same in a plane parallel to the face of the core of said electromagnet to effect contactual engagement of said contact 45 springs to close a circuit through said contact springs and operable by gravity to discontinue the contactual engagement of said contact springs to open the circuit 50 through said contact springs.

5. A device of the class described including an electromagnet, a mounting member having an integrally and right angularly formed ear, means for securing said electromagnet to said ear so that said electromagnet is parallel to said mounting member, a contact spring secured to said mounting plate member and having its one end adapted to receive a conductor, a pendulous 55 armature having a contact spring secured to said supporting means in such a position

its one end, means including an adjustable screw adapted to adjust the pivotal movement of said armature and to be locked in its adjusted position secured to said mounting member for pivotally supporting and 70 positioning said armature upon said mounting member so that the other end of said armature is positioned in a vertical plane parallel to the axis of the core of said electromagnet and in operative position with 75 the core of said electromagnet and its contact spring in operative position relative to said first contact spring, said armature having a normally balanced position so that said contact springs do not engage each other but adapted to assume a position to effect contactual engagement of said contact springs when said electromagnet is energized to cause said armature to move in a plane parallel to the face of the core of said 85 electromagnet to effect said contactual engagement.

6. An alternating current relay of the class described including an electromagnet, a supporting member for supporting said electromagnet, a contact spring secured to said supporting member, a pendulous armature having a contact spring secured thereto, means for pivotally supporting said armature in a vertical plane parallel to the axis 95 of the core of said electromagnet and in operative position relative to the said core of said electromagnet, said means including an adjustable screw adapted to adjust the pivotal movement of the armature and to be 100 locked in its adjusted position, said armature operable by said electromagnet to move said armature in a plane parallel to the face of the core of said electromagnet to effect contactual engagement of said contact 105 springs and operable by gravity to discontinue the contactual engagement of said contact springs when said electromagnet is deenergized.

7. A device of the class described including a mounting member having an integrally formed right angular ear, an electromagnet secured to said ear and parallel to said mounting member, a contact spring secured to said mounting member parallel to 110 said electromagnet, a pendulous armature having a contact spring secured to its one end, means including an adjustable screw adapted to adjust the pivotal movement of the armature and to be locked in its adjusted 115 position for pivotally supporting said armature in a vertical plane parallel to the axis of the core of said electromagnet and in operative position relative to said electromagnet and said second contact spring in 120 operative position and at right angles to said first contact spring, said armature having its other end shaped and of such weight that said armature is normally balanced in 125 operative position in such a position

that said contact springs are out of engagement and also adapted to be moved in a plane parallel to the face of the core of said electromagnet when said electromagnet is energized to effect contactual engagement of said contact springs to close a circuit through said springs.

8. A device of the class described including a mounting member, an electromagnet secured thereon, a contact spring secured on said mounting member and parallel to said electromagnet, a pendulous armature having a contact spring secured to its one end, supporting means including an adjustable screw adapted to adjust the pivotal movement of the armature and to be locked in its adjusted position, for pivotally supporting said armature near its said one end, secured on said mounting member in such position that the said second contact spring is at right angles to said first contact spring and the free end of said armature lies in a vertical plane parallel to the axis of the core of said electromagnet, said free end of said armature adapted to balance said armature in said means so that said contact springs do not engage each other and also adapted to be attracted by said electromagnet to cause said armature to move in a plane parallel to the face of the core of said electromagnet to effect contactual engagement of said contact springs to close a circuit through said contact springs.

9. A device of the class described including a mounting member, an electromagnet secured thereon, a contact spring secured on said mounting member and parallel to said electromagnet, a pendulous armature having a contact spring secured to its one end, supporting means, for pivotally supporting said armature near its said one end including an adjustable screw adapted to adjust the pivotal movement of the armature and to be locked in its adjusted positions, secured on said mounting member in such position that the said second contact spring is at right angles to said first contact spring and the free end of said armature lies in a vertical plane parallel to the axis of the core of said electromagnet, said free end of said armature adapted to balance said armature in said means so that said contact springs do not engage each other and adapted to be attracted by said electromagnet to cause said armature to move in a plane parallel to the face of the core of said electromagnet to effect contactual engagement of said contact springs to close a circuit through said contact springs, a mounting plate, and means for securing said mounting member on said mounting plate in such position that said armature assumes a vertical position.

10. A device of the class described including a mounting member, an electromagnet

and a contact spring mounted thereon parallel to each other, a pendulous armature having a contact spring secured thereto, means, for pivotally supporting said armature including an adjustable screw adapted to adjust the pivotal movement of said armature and to be locked in its adjusted positions, secured to said mounting member so that said contact springs are at right angles to each other and said armature lies in a vertical plane parallel to the axis of the core of said electromagnet, said armature being balanced vertically in said supporting means to normally maintain said second contact spring out of engagement with said first contact spring and adapted to be operated by said electromagnet to cause said armature to move in a plane parallel to the face of the core of said electromagnet to effect contactual engagement of said contact springs upon the energization of said electromagnet.

11. A device of the class described including a mounting member, an electromagnet and a contact spring mounted thereon parallel to each other, a pendulous armature having a contact spring secured thereto, means, for pivotally supporting said armature including an adjustable screw adapted to adjust the pivotal movement of said armature and to be locked in its adjusted positions, secured to said mounting member so that said contact springs are at right angles to each other and said armature lies in a vertical plane parallel to the axis of the core of said electromagnet, said armature being balanced vertically in said supporting means normally maintain said second contact spring out of engagement with first contact spring and adapted to be operated by said electromagnet to cause said armature to move in a plane parallel to the face of the core of said electromagnet to effect contactual engagement of said contact springs upon the energization of said electromagnet, said armature and its contact spring restoring the normal position by gravity upon the de-energization of said electromagnet to break the connection of said contact spring.

12. A device of the class described including a mounting member, an electromagnet and a contact spring secured on said mounting member parallel to each other, a pendulous armature having a contact spring secured to its one end, means including an adjustable screw adapted to adjust the pivotal movement of said armature and to be locked in its adjusted positions for pivotally supporting said armature in a vertical plane parallel to the axis of the core of said electromagnet and in operative position relative thereto, and its associated contact spring at right angles to said first contact spring, said armature having its free end adapted to be attracted by said electromagnet and move in a plane parallel to the face of the

- core of said electromagnet to effect contact-
ual engagement of said contact springs to
close a circuit through said contact springs
when said electromagnet energizes, and
adapted to restore to normal position by
gravity to effect disengagement of said con-
tact springs and to maintain said contact
springs out of engagement when said electro-
magnet de-energizes.
- 10 13. A device of the class described includ-
ing a mounting member, an electromagnet
mounted on said mounting member, a contact
spring secured on said mounting member par-
allel to side electromagnet, a pendulous ar-
mature lying in a vertical plane parallel to
the axis of the core of said electromagnet and
having its one end reduced and its other end
enlarged, a contact spring secured to the re-
duced end of said armature, means, for pivot-
ally supporting said armature at its reduced
end including an adjustable screw adapted to
adjust the pivotal movement of said arma-
ture and to be locked in its adjusted posi-
tions, secured to said mounting member and
positioned so that said second contact spring 25
is in operative position and at right angles
to said first contact spring and said enlarged
end is partially in alignment with a portion
of one end of the core of said electromagnet,
said armature normally balanced vertically 30
in said supporting means to maintain said
contact springs out of engagement with each
other, and said enlarged end adapted to be
attracted upon the energization of said elec-
tromagnet and to move in a plane parallel to 35
the face of the core of said electromagnet into
full alignment with the end of the core of
said electromagnet to effect contactual en-
gagement of said contact springs.

Signed by me at Jamestown, in the county 40
of Chautauqua, and State of New York, this
14th day of April, 1924.

HENRY ROBERT SPENCER.
